STEAM BOILER AND MERCURY
CONDENSER

Charles E. Lucke, New York, N. Y., assignor to
The Babcock & Wilcox Company, Bayonne,
N. J., a corporation of New Jersey

Application August 4, 1928, Serial No. 297,456
Renewed August 25, 1932

2 Claims. (Cl. 122—32)

This invention relates to a steam boiler and mercury condenser that can be made of standard boiler parts, and is especially useful in connection with mercury vapors that contain uncon-
5 densable gases, but it is not restricted to this par-
ticular use.

The invention will be understood from the description in connection with the accompanying drawings in which Fig. 1 is a vertical section along 10 the line 1—1 of Fig. 2 through an illustrative embodiment of the invention; Fig. 2 is an end view of Fig. 1 with parts removed; Fig. 3 is a vertical section along the line 3—3 of Fig. 4 showing a modification, and Fig. 4 is an end view of Fig. 3 with parts removed.

In the drawings, reference character 1 indicates an inclined shell in the form of a cylinder that is provided with an inlet 2 on its lower side near the upper end for mercury vapors from a mercury 20 boiler (not shown). A hood 3 is provided above the inlet to prevent condensate from dropping back through the inlet and a flange 4 is provided around the inner end of the inlet to prevent liquid condensate from running back into the inlet. 25 Baffles 5 extend upwardly from the lower side of the casing 1 and baffles 6 extend downwardly from the upper side, these baffles being spaced apart such distances that vapor passes of decreasing areas toward the outlet are provided. An outlet 30 7 is provided at the lower end near the upper side of the casing 1 and may be connected to a vacuum pump for removing non-condensable gases. Drains 8 are provided along the lower side of the casing 1 to remove condensate that collects behind 35 the baffles 5 or along the lower side of the casing 1. The pipes 8 extend to a collector 9, from which collector a pipe 10 may extend to a mercury boiler for generating vapors to be introduced through the inlet 2.

40 Inclined tubes 12 are installed inside of the casing 1 parallel to its axis. The lower ends of these tubes are connected to downtime headers 13, while the other ends thereof are connected to uptake headers 14. The different headers in the 45 groups 13 and 14 are made of different lengths, as most clearly indicated in Fig. 2, so as to occupy substantially the entire cross-sectional area of the cylindrical casing 1.

A cross drum 15 extends above the lower end 50 of the casing 1 and the lower side thereof is connected by nipples 16 to the upper ends of the headers 13, and these nipples preferably pass radially through the shell or casing 1. Nipples 17 extend from the lower ends of the headers 13 to a semi-circular header 18 below the casing 1, the

nipples 17 preferably passing radially through the wall of the casing. The ends of the header 18 are connected by pipes 19 to the lower side of the cross drum 15.

Nipples 20 connect the upper ends of the headers 14 to a row of boxes 21 on the outside of the casing 1, these nipples also preferably passing radially through the wall of the casing. The junction boxes 21 are connected to the cross drum 15 by means of tubes 22.

60 The operation is as follows: Mercury vapors enter the casing 1 through the inlet 2 and pass a plurality of times across the tubes 12 around the edges of the baffles 5 and 6, as indicated by the arrows. The condensed mercury passes to the 70 lower side of the casing, thence out through the pipes 8 to the collector 9 and back to the mercury boiler. The uncondensable gases in the mercury vapors are forced forward because of the decreasing cross-sectional area of the mercury 75 vapor passages and are at last drawn out through the outlet 7 by means of the vacuum pump. The casing 1 is preferably made cylindrical since this form will enable it to withstand either internal or external pressures of considerable magnitude 80 without requiring very thick walls.

The water in the cross drum 15 passes downwardly through the nipples 16 into the headers 13 and also through the pipes 19 into the header 18, and thence through the nipples 17 into the 85 headers 13. The water passes upwardly from the headers 13 through the inclined tubes 12 where steam is generated. The mixture of steam and water enters the uptake headers 14 and passes through the nipples 20 and tubes 22 into 90 the cross drum 15 from which the steam can be taken in the usual manner for use.

In the modification shown in Figs. 3 and 4, the parts already described are indicated by the same reference characters and will not be again described. In this modification, the header 18' is made straight instead of semi-circular and the tubes 20' extend directly from the upper ends of the headers 14 to the cross drum 15 instead of extending into junction boxes as in Figs. 1 and 2. 100 The operation is similar to that already described.

Changes and modifications can be made without departing from the spirit and scope of the invention.

105 I claim:

1. A steam boiler and a condenser for vapors of high boiling point liquids, comprising an inclined bank of tubes having headers, an enclosing vapor-tight shell for the said bank, means for 110

introducing vapors of a high boiling point liquid into said shell at one end thereof, an outlet for non-condensable gases at the opposite end of said shell approximate the top, depending baffles intermediate the ends of the shell and cooperating with intermediate oppositely extending baffles to form a tortuous path for the vapors back and forth across the tubes from entrance to outlet of the condensate, the baffles being positioned with respect to each other to provide a vapor passage of continually decreasing area to maintain velocity of vapors over the tube from entrance to outlet as the vapor volume decreases due to condensation, and means draining condensate from the compartments set off by the oppositely extending baffles hereinabove identified.

2. A steam boiler and a condenser for vapors of high boiling point liquids, comprising an inclined bank of tubes having headers, an enclos-

ing vapor-tight shell for the said bank, means for introducing vapors of a high boiling point liquid into said shell at one end thereof, an outlet for non-condensable gases at the opposite end of said shell approximate the top, depending baffles intermediate the ends of the shell and cooperating with intermediate oppositely extending baffles to form a tortuous path for the vapors back and forth across the tubes from entrance to outlet of the condensate, the baffles being positioned with respect to each other to provide a vapor passage of continually decreasing area to maintain velocity of vapors over the tube from entrance to outlet as the vapor volume decreases due to condensation, and means separately draining condensate from each compartment set off by the oppositely extending baffles hereinabove identified.

CHARLES E. LUCKE.
